CLAIM

The ornamental design for an antimicrobial decontamination device, as shown and described.

DESCRIPTION

FIG. 1 is a frontal perspective view of an antimicrobial decontamination device showing my new design;

FIG. 2 is a partial, enlarged frontal perspective view of a head portion of the antimicrobial decontamination device shown in FIG. 1;

FIG. 3 is a top plan view of the antimicrobial decontamination device shown in FIG. 1;

FIG. 4 is a front elevational view of the antimicrobial decontamination device shown in FIG. 1;

FIG. 5 is a left-side side elevational view of the antimicrobial decontamination device shown in FIG. 1, wherein an elevational view of the right side is a mirror image thereof;

FIG. 6 is a rear elevational view of the antimicrobial decontamination device shown in FIG. 1;

FIG. 7 is a bottom plan view of the antimicrobial decontamination device shown in FIG. 1;

FIG. 8 is a rear perspective view of the antimicrobial decontamination device shown in FIG. 1; and,

FIG. 9 is a partial, enlarged rear perspective view of the head portion of the antimicrobial decontamination device shown in FIG. 1.

The broken line portions of the drawing figures are included to show unclaimed subject matter only and form no part of the claimed design.

1 Claim, 3 Drawing Sheets
